[57] CLAIM

The ornamental design for a handle for a powered lawn and garden implement, as shown and described.

DESCRIPTION

FIG. 1 comprises a perspective view, taken from the right and from the front, of one embodiment of a handle for a powered lawn and garden implement according to the present invention;

FIG. 2 is a left-side elevational view thereof the opposite side being symmetrical;

FIG. 3 is a top plan view thereof;

FIG. 4 is a bottom front perspective view thereof;

FIG. 5 is a perspective view, taken from the right and from the rear, thereof;

FIG. 6 comprises a perspective view taken from the right and from the front of the second embodiment thereof;

FIG. 7 is a left-side elevational view thereof the opposite side being symmetrical;

FIG. 8 is a front perspective view thereof;

FIG. 9 is a bottom front perspective view thereof; and,

FIG. 10 is a rear perspective view, taken from the right and from the rear, thereof.

The broken lines are shown in the views for illustrative purposes only and form no part of the claimed design.
